UNITED STATES PATENT OFFICE

ARTHUR FRIEDMAN, OF CLEVELAND, OHIO, ASSIGNOR TO THE CLEVELAND HEATER COMPANY, OF CLEVELAND, OHIO, A CORPORATION OF OHIO

WATER HEATER CIRCULATING COIL

Application filed March 3, 1928. Serial No. 258,872.

This invention relates to improvements in gas fired liquid heaters and in particular to the circulating coils for gas burning domestic water heaters.

5 It has for its object the provision of a water heater circulating coil that is inexpensive and easy to manufacture, and that is more durable than the ordinary type of circulating coils, and that is protected 10 against the destructive action of the condensation products of combustion of the gaseous fuels used in gas burning water heaters.

My invention, in general, consists in the provision of guard rings, to divert and evaporate the condensed products of combustion, which collect and accumulate on the lowermost portion of coils of gas fired water heaters, and which are regarded as the principal cause of failure in coils of this type.

20 In the usual construction of copper heater coils of the ordinary type, there is a decided tendency to failure at the point of the coils, where they enter the lower coupling member. This disintegration of the copper 25 from which the coils are made, is usually accompanied by the formation of copper sulphate at the point of failure of the coil. It is common knowledge that most commercial gases particularly manufactured gas, 30 upon burning give off an oxide of sulphur, as well as water vapor.

The accepted theory of this phenomena is that the condensation of water vapor, which takes place on the heater coils, causes 35 the formation of sulphurous acid by combining with the vaporous sulphur compound given off by the burning gas.

As the weak sulphurous acid thus formed on the heater coils runs to the bottom of the 40 coils, a certain amount of it is converted into sulphuric acid, by reason of coming in contact with what copper oxide may be present on the heater coils.

45 The acids thus formed collect at the point of the coils where they enter the coil coupling. At this point, there is apt to be present considerable copper oxide, if it is a brazed joint. The oxide referred to is present as a result of the action of the gas flame used in the brazing operation.

Furthermore, the copper tubing at the brazed joint is somewhat weakened, due to the heat applied in brazing, which causes some oxidation as well as annealing, both of which are apt to leave this portion of the 55 copper tubing in a condition in which it is more susceptible to the corrosive action of sulphuric action than the other portions of the tube.

Disregarding for the moment, the type of 60 joint between the tubing and the coupling, whether it be a brazed joint or a union coupling, it is apparent that a part of the aforementioned liquids, condensed from the products of combustion of the gaseous fuel, come 65 to rest at the junction of the coupling and the coils.

At this junction point, which is in close 70 proximity to the heater burner, the condensation products are further concentrated by direct action of the flame and evaporation of excess water in the acid solution, producing concentrated sulphuric acid, which readily combines with the copper of the 75 heater coil.

It is upon this theory, which is supported 80 by the presence of copper sulphate at the junction of the coupling and the tubing, after the heater has been in use for some time, that the common cause of failure of the copper coils of water heaters is accounted for.

The formation of scale and liming of 85 the interior of the heater coils accelerates their deterioration. Under these conditions, when in operation, the heater coils are kept at a much higher degree of temperature, due to the low thermal conductivity of the fouled tubing, and in addition to being more rapidly disintegrated by sulphuric acid, the 90 coils are also oxidized by the direct action of the burner flame.

The primary object of this invention is to 95 prevent the accumulation of the harmful condensation products of combustion at the weakest part of the coil. This result is accomplished in my improved coil, by the provision of guard rings, which are highly resistant to heat and to the action of sulphuric acid and which by reason of their shape and 100

construction can be maintained at a higher temperature than the water heater coils or coupling.

This invention is particularly useful in water heaters in which the ends of the circulating coils are brazed in the heater coupling, as the coils are somewhat weakened by this operation, due to the high heat which is applied to them and to the action of the fluxes which are used in brazing.

10 The accompanying drawing shows a front elevation, partly in section, of a water heater constructed in accordance with, and adapted for use in practicing my invention.

15 Referring to the drawing, the reference numeral 1, indicates the heater casing or jacket of a conventional gas fired domestic water heater. This casing provides a housing for the copper circulating coils 2 which are adapted to be put in communication 20 with the storage vessel by means of the lower and upper union-connections 3 and 4, respectively.

25 Means for applying heat to the coil is provided for by the gas burner 5, which is mounted on an air and gas mixing tube 7, of the venturi type. The burner 5 is positioned below the coils in the lower portion 30 of the heater jacket. A gas cock 8 is mounted at the inlet end of the mixing tube 7, and is adapted to be connected to a source of gas supply.

35 Guard rings 9, are secured in any suitable manner around the heater coils at a point adjacent the lower coupling. This may be accomplished by forming the rings to snugly fit the tubing and slipping them over the tubing before the coupling is attached. A split guard ring may be used, permitting its 40 application to the coil after the coupling is in place. The guard rings may be made of any suitable material, and it is particularly desirable to make them from a material which is not readily affected by the harmful 45 ingredients in the products of combustion from the ordinary gaseous fuels.

50 In the present instance, the rings are made of pure iron, which material has been found to be suitable for this purpose. 55 Other materials could be used and it might be advisable in some cases to make these rings from copper, brass, or a ceramic material. When made of a material, similar to the material used in the construction of the circulating coils, such as copper or brass, the effect of the rings would be to lengthen the life of the coils in proportion to the thickness of the guard ring. In this case it would be necessary for the rings to 60 corrode first before the tubes can be attacked, due to the acid settling to the lower-most portion of the ring and combining with the material of the ring before attacking the tubing.

65 It is apparent that my improved heater

coil could be used in conjunction with oil burning water heaters as well as gas burning water heaters and that it could be used to advantage in the heating of liquids other than water, where said coils are subjected to treatment similar to that which they receive in gas fired water heaters.

70 Furthermore, it is to be understood that the particular forms of apparatus shown and described, and the particular procedure set forth, are presented for purposes of explanation and illustration and that various modifications of said apparatus and procedure can be made without departing from my invention as defined in the appended 75 claims.

80 Having described my invention, I claim:

1. A gas fired water heater comprising, a heater casing, vertically arranged tubular circulating coils housed in said casing, a coupling member bonded to the lower ends of said coils so as to form an integral irre- 85 movable part thereof, means to apply heat to said coils, and means adjacent said coupling member carried by said coils to prevent the condensation products of combustion deposited on said coils from flowing to and collecting at the joint between said coupling member and said coils.

90 2. In a liquid heater, a circulating coil, a coupling member permanently brazed to the lower end of said coil so as to form an integral irre- 95 movable part thereof, and means adjacent to and spaced from said coupling member to prevent the collection of condensate at the joint between the coupling member and the coil.

100 3. In a liquid heater, a circulating coil, a coupling member bonded to the lower end of said coil so as to form an integral irre- 105 movable part thereof, and a ring of a material more resistant to the action of an acid than the material of the coil encircling said coil at a point adjacent said coupling member to prevent the collection of condensate 110 at the joint between said coil and coupling member.

115 4. In a gas fired water heater, a vertically arranged tubular water circulating coil, a coupling member bonded to the lower end of said coil so as to form an integral irre- 120 movable part thereof, a gas burner for supplying heat to said circulating coil, and means comprising a guard ring made of a material relatively unaffected by the condensation products of combustion as compared with the material of the coil encircling said coil at a point adjacent said coupling for the purpose of preventing corrosion of the portion of said coil adjacent 125 said coupling member.

130 5. The combination of a water heater circulating coil formed from a section of copper tubing, a coupling member brazed thereto, and an iron ring encircling and sup-

ported on said coil at a point adjacent its lower extremity and spaced from said coupling member for the purpose of preventing the condensate deposited on said coil from 5 collecting at the junction of said coil and coupling member.

6. The combination of a water heater coil of metal tubing, a coupling member brazed thereto, and a guard ring encircling and 10 supported on said coil at a point adjacent the lower extremity of the coil and spaced from said coupling member for the purpose of preventing the condensate deposited on said coil from collecting at the junction of 15 said coil and coupling member.

In testimony whereof I affix my signature.
ARTHUR FRIEDMAN.
